UNITED STATES PATENT OFFICE.

J. HERBERT PEARSALL, OF WELLSVILLE, NEW YORK.

CLOTHES-DRIER.

SPECIFICATION forming part of Letters Patent No. 328,968, dated October 27, 1885.

Application filed April 6, 1885. Serial No. 161,330. (No model.)

To all whom it may concern:

Be it known that I, J. HERBERT PEARSALL, a citizen of the United States, residing at Wellsville, in the county of Allegany and State of New York, have invented certain new and useful Improvements in Clothes-Driers, of which the following is a specification, reference being had therein to the accompanying drawings.

10 My invention relates to improvements in clothes driers or racks, having for its object the provision of a rack adapted to be secured to a wall and to be raised and lowered in an inclined horizontal or vertical position, so as 15 to lie at different angles to said wall, as desired; and to these ends the invention consists in the construction, arrangement, and combinations of the various parts, substantially as hereinafter fully set forth, and particularly 20 pointed out in the claims.

In the drawings hereto annexed, Figure 1 is a side elevation of a clothes drier or rack embodying my invention, and held extended at an angle from a wall, the different degrees 25 of inclination being indicated in dotted lines. Fig. 2 is a front elevation thereof. Figs. 3, 4, 5, and 6 are detail views of parts of my improvements.

Referring to the drawings, in which like 30 letters of reference indicate like parts in all the figures, A designates the drier proper, comprising longitudinal side rails, a , transverse rails a' , and a lower pivotal rail, a'' . The rails are held together by straining-rods B that 35 pass from side to side of the frame and through the longitudinal side rails thereof. I preferably employ three straining-rods, which are each provided at one end with a swelled head, against which fits a washer, b , and at the opposite end thereof with a screw-thread which 40 receives a thumb-nut, b' , adapted to bear against the outer face of one of the side rails a and draw the frame tightly together. The rail a'' is mounted in screw-hooks a^3 , which are 45 screwed into the wall and thus support the rack, while it is free to move therein in raising and lowering it, and can be readily removed therefrom by simply lifting it bodily from out of contact therewith. The said rail 50 a'' is connected to the side rails, a , by elbows a^4 , which are provided with flaring or enlarged

mouths or sockets, into which are driven the lower transverse rail and the side rails, as is obvious, thus securely connecting them together.

C designates a spring-drum, mounted on a shaft or pin, d , in a bracket or support, D, which is bifurcated to provide two arms, D' D'' , and has a shank, d' , which is screw-threaded, thus adapting the bracket to be screwed into the wall or other place. The shaft or pin d is mounted in the arms D' at the ends thereof and between the same, said shaft having one of its ends flattened or made square and fitting in a corresponding-shaped socket in the arms, 65 for a purpose presently described. The sockets in the arms for the shaft d open or extend to the upper edges of the arms, thus adapting the shaft and drum to be readily placed in position and removed when desired without removing the rack—as for instance, when the spring within the drum requires repairing.

The drum C consists of a cylindrical shell, c , and two heads, c' , which are riveted to the shell, or the shell may be cast in one piece 75 with one of the heads and the other riveted thereto. Within the drum thus formed is placed a coiled spring, E, one end of which is secured to the shell c on the interior surface thereof, as at c' , while the other end is secured 80 to the shaft d , passing centrally through the heads and casing, as clearly shown.

The drum and bracket are secured to a wall at a point opposite the top rail and a little below the plane thereof.

85 A cord, rope, or wire, F, is connected at one end to the drum, and at its other end to the top rail of the rack, to maintain the same in any desired position, as will be more fully presently described.

90 One of the heads c' of the drum is provided with a ratchet, f , on its exterior face, either secured thereto, but, preferably, cast therewith in one piece, with which a pawl, G, is adapted to engage, said pawl being pivoted 95 to one of the arms of the bracket D, as at g , and provided with an extension or nib, to which is connected a cord, H, which passes down to an eye, h , and thence horizontally to another eye, h' , secured to the wall outside of 100 the rack, and thence downwardly again, and provided with a weight, I. It will be observed

from this construction that the weight I and cord H serve to hold the pawl G in contact with the ratchet, and that when the rack is extended at an angle to the wall the weight 5 thereof will also tend to hold the pawl in position against the ratchet, thus obviating the danger of the pawl becoming disengaged and allowing the rack to fall forward, causing the breakage of the several parts.

10 The operation of my invention is as follows: When the rack is in a vertical position, and it is desired to lower the same to allow clothes or other articles to be hung thereon, the weight I is elevated to allow the pawl to drop out of 15 engagement with the ratchet. The rack will now tilt forward by gravity, or be lowered by hand to the desired position, after which the weight is dropped, thereby causing the pawl to again engage the ratchet and thus hold the 20 drum from rotating and the rack in position. It will be observed that when the rack is tilted forward the cord F will rotate the drum C and put the spring E under tension, and that the weight of the rack will hold the pawl in contact with the ratchet.

When the rack is to be raised to a vertical position, it is elevated by hand to that position, the recoil of the spring serving to rotate the drum C and automatically take up the 30 slack in the cord F and wind the same thereon.

It will be observed that my invention is light, strong, simple, and durable in construction, and that it can be readily and quickly put up in position in a kitchen or other place, 35 it being only necessary to first place the screw-hooks a^3 in position, then the spring-drum, then the rack proper, and properly connect the cords F and H. The device is also automatic in its action, and requires but very little effort on the part of the operator to raise 40 and lower the rack.

Modifications in details of construction and form, proportion, and arrangement of the several parts herein shown and described as an 45 embodiment of my invention can be made without departing from the principle or sacrificing the advantages thereof—as, for instance, in lieu of the weight a spring can be employed to hold the pawl in contact with the ratchet

and the operating-cord connected to said pawl 50 forward of the pivot thereof. I would therefore have it understood that I hold myself at liberty to make such changes in the details of construction as fairly fall within the scope of my invention.

What I claim as my invention, and desire to secure by Letters Patent of the United States, is—

1. In a clothes-drier, the combination of a rack composed of side and transverse rails 60 and hinged to a wall with a spring-drum secured to a wall and free to rotate upon its axis, and a cord connecting said drum and rack, substantially as and for the purpose set forth.

2. In a clothes-drier, the combination of a rack pivotally supported upon a wall with a spring-drum having a ratchet, a cord connecting said drum and rack, a pawl, and an operating-cord, substantially as and for the 70 purpose set forth.

3. In a clothes-drier, and in combination with the rack pivotally supported in hooks and adapted to be held at different angles, a spring drum mounted in a bracket secured to 75 a wall about on the plane of the top of the rack, a cord connecting said drum and rack, a ratchet secured to the drum, a pawl pivoted to one of the arms of the drum-supporting bracket, and an operating-cord connected to said pawl, substantially as and for the purpose set forth.

4. In a clothes-drier, a rack hinged at its lower end, and consisting of side and transverse rails, and straining-rods B, having thumb-nuts, in combination with a spring-drum, C, 85 mounted in bracket D, having a screw-threaded shank, d, cord F, connected to said drum and the upper rail of the rack, ratchet f, secured to said drum, pawl G, pivoted to one of the arms of the bracket, a cord, H, weight I, 90 and eyes h', through which said cord passes, substantially as and for the purpose set forth.

In testimony whereof I affix my signature in presence of two witnesses.

J. HERBERT PEARSALL.
